(57) **CLAIM**

The ornamental design for a lantern light, as shown and described.

DESCRIPTION

FIG. 1 is a front view of a lantern light in accordance with my invention;

FIG. 2 is a back view thereof;

FIG. 3 is a left view thereof;

FIG. 4 is a right view thereof;

FIG. 5 is a top view thereof; and,

FIG. 6 is a bottom view thereof.

The long-short dash broken lines in FIGS. 1-4 show the light element behind the lens portion. The evenly dashed broken lines in FIG. 5 show recessed details. All broken lines show portions of the Lantern Light which form no part of the claimed design.
